UNITED STATES PATENT OFFICE.

GEORGE E. MARLATT, OF PASADENA, CALIFORNIA.

TYPE-CASTING MECHANISM FOR LINOTYPE-MACHINES.

1,263,265.

Specification of Letters Patent. Patented Apr. 16, 1918.

Application filed February 24, 1914, Serial No. 820,787. Renewed September 25, 1916. Serial No. 122,311.

To all whom it may concern:

Be it known that I, GEORGE E. MARLATT, a citizen of the United States, residing at Pasadena, in the county of Los Angeles and State of California, have invented a new and useful Improvement in Type-Casting Mechanisms for Linotype-Machines, of which the following is a specification.

My invention relates to type casting mechanism for linotype machines and more particularly to the slug ejecting mechanism associated with said mechanism, and has for its object the provision of a universal means for ejecting the slugs from the mold after the casting operation; a more efficient and automatic arrangement of some of the closely related parts of the casting mechanism; reducing the amount of manual effort required for the operation of said mechanism to a minimum; and a general simplifying of the elements of the type casting mechanism.

Other objects may appear in the subjoined detailed description of my device as illustrated in the accompanying drawings in which Figure 1 is a perspective view of my universal ejector; Fig. 2 is a side elevation of one of the multiple ejector members with the corresponding sizes of the other members indicated in dotted lines; Fig. 3 is an end elevation of Fig. 1, partly broken away; Fig. 4 is a sectional elevation on the line 4—4, Fig. 1, of the ejector base and slide; Fig. 5 is a perspective of the same; Fig. 6 is a sectional elevation on the line 6—6, Fig. 4, of the ejector rack and worm; Fig. 7 is a fragmentary side elevation of the right hand ejector blocks showing the removing means for one of the ejector blades; Fig. 8 is a sectional elevation through the casting slot of the mold and the ejector blade guide; Fig. 9 is a sectional plan of a linotype machine showing the relation of my apparatus thereto, with certain parts of the machine omitted; Fig. 10 is a section of the mold disk drive shaft, showing the face of one of the jaw clutches; Fig. 11 is a longitudinal section of the mold disk drive shaft showing the clutch members out of engagement; Fig. 12 is a side elevation of a linotype machine showing my apparatus in operative position thereon.

Similar characters of reference indicate the same parts throughout the specifications and the several views of the drawings.

In my mechanism, as hereinafter described, many changes of minor importance

have been made in the general outlines and relationship of some of the old parts typical of linotype machines, in order to adapt the machine to use in connection therewith, and the mechanism disclosed provides a re-arrangement of the relative positions of the mold disk and driving pinion, with the latter placed at the bottom of the former on the vertical center line.

My universal and variable ejecting mechanism is designed to simplify the operation of a slug casting machine, to economize in time and labor and to generally facilitate the ejection of the slugs from the molds, and I provide a plurality of ejector blades of various widths mounted in sets of four, in an arbor, and both laterally and pivotally adjustable in order to readily place any desired blade in alinement with the casting slot of the mold for the ejecting operation.

The base 107 is rigidly mounted on the frame of the machine and has a lateral groove 108 about centrally disposed between the ends with the countergroove 109 on each side thereof and at the bottom of the former. The ejector carriage 110 has a floor 111 and two upwardly extending sides 112, the upper ends of which are provided with the forward extension 113 and the rear extension 114 which is slightly longer than the former. The carriage is adapted to slide laterally in the central groove 108 and the floor 111 has the extensions 115 adapted to engage and slide in the countergrooves 109; the side of the floor having the rack 116 extending therefrom and provided with the grooves 117 adapted to be engaged by the threads on the worm 118 which is revolvably mounted in the base 107, centrally with 95 and below the carriage 110 in the bore 119 and on the shaft 120 which is provided with a collar 121.

Between the sides 112 of the carriage are mounted the ejector slides 122 having the recesses 123, in each of which is mounted on an arbor 124, one of the multiple ejectors 125 having the blades 126, the lower edge 127 of each of the blades on the ejectors being an equal distance from the center, and the lower edges of opposite blades being parallel.

For convenience in assembling, each of the slides 122 have the plates 128 secured thereto by the screws 129, the plates serving 110 to close one side of the recesses 123, and the base 107 is provided with a longitudinal

groove 130 which has a countergroove 131 at the bottom and which extends the entire length of the base, and at the forward end in the groove 108 is provided with a shelf 5 132 adapted to register with the bottom of the groove 130. The groove 130 is adapted to align vertically with the casting slot 133 in the mold and the ejector slides are adapted to slide forward in this groove in 10 an ejecting operation, as shown in Fig. 1.

The blades 126 are so arranged in position on the ejectors as to give an ascending scale 15 of widths of the slugs both around their center and laterally across the carriage, the width of the blade corresponding in all cases to the length of the slugs that are cast and ejected by a particular blade, and the number of blades and the arrangement shown covers the entire range of sizes required for the ejection of all lengths of slugs. I make one of the blades 134 removable so that blades of irregular or narrower widths may be substituted therefor, the ejector being provided with a slot 135 and the blade 20 being secured in the slot and prevented from removal therefrom by a pin 136 secured in the inner end of the blade and adapted to engage an annular groove 137 in the plate 128, the pin 136 being secured also 25 in a flange 138 adjacent to the blade. The pin 136 in its relation with the groove 137 locks the blade 134 against removal, and the outlet 137' to the groove 137 serves to permit the removal of the blade.

35 The rear ends of the slides 122 are provided with a circular groove 139 with the edges beveled as in other machines the end of the ejector lever 140 being adapted to seat in a desired one of the slides for ejecting a 40 slug from the mold, and an arm 141 having a groove 142 in which the lever 140 is held by the top plate 143, is secured to the frame of the machine as a steady means for the arm. The slides 122 are placed in operative 45 relation with the lever 140 by moving them laterally with regard thereto and causing the engagement of the lever end with the groove 139. The ejector slide has a resilient brace rod 144 mounted upon it which is 50 pivoted to the top edge of the slide 122 on a pin 145; the rod 144 also has a rear lug 146 adapted to engage a stop pin 147 secured in the slide to limit the inward movement of the brace rod, a spring 147' being 55 secured at one end to the upper edge of the slide and at the other end looped around a pin 147 for holding the front end 148 of the rod resiliently in engagement with the blades 126, and this front end is tapered toward the front so that the front edge will 60 enter and engage the edge of the perforation 149 in the blades and thus prevent a backward movement thereof, but backwardly from the end to permit a forward movement of the blades around their axis.

One of the brace rods 144 is provided for each of the slides, although not shown in Fig. 1 to avoid obscuring other parts.

Each of the arbors 124 has a central square perforation 124' and in these perforations 70 the rod 150 which has the squared end 150' is adapted to slide laterally against the tension of the spring 151 when forced in by the operator, for turning the ejectors and placing three of the blades 126 in selective position. The rod 150 is slidable also in the column 152 of the frame of the machine, is provided on the inside of the column with a flanged collar 153 secured to the rod 150 by the screws 154 and has four equally spaced 80 perforations concentrically arranged around its face adapted to receive the pin 155 which is secured in the column. Thus the collar 153 may be radially adjusted by forcing it off of the pin 155 and turning the rod 150 85 so that another of the perforations may be engaged by the pin, the sets of blades being thus turned by quarters.

The outer end of the rod 150 has a suitable crank 156 to facilitate the turning thereof and also a collar 157 which is secured to the rod by a screw 158, between which collar and the column, the spring 151 is adapted to be compressed. When the rod is forced into a position in the ejectors and the latter are 95 turned, the rod may be thus restored by the spring. As a means for visibly indicating the proper position of the rod 150 for each of the blades 126, I provide a pin 160 which is secured to the inner side 112 of the carriage, extends into the column 152 and carries an index shield 161 which covers the rod 150 and has a suitable perforation 162 through which may be seen a number representing a certain blade, the numbers being 100 marked on the rod 150.

The worm shaft 120 is also revolvably mounted in the column 152 of the machine, is provided on its outer end with a crank 163 made slidable thereon by means of a screw 110 164 in a slot 165 in the shaft 120, and has an arm 166 secured thereto which is connected with the crank 163 by a rod 167 secured to the crank and slidable in the arm 166. The inner end of the rod 167 is adapted to seat 115 in a suitable perforation in the column 152, and the outer end of the shaft 120 is provided with a spring 168 adapted to be compressed between the arm 166 and the crank 163, the rod 167 serving to lock the worm 120 shaft against rotary movement.

When it is desired to place one of the slides 122 in operative position, the crank 163 may be pulled outwardly and the rod 167 released from its seat in the column 152, 12 the shaft 120 may then be turned in the proper direction, and by the engagement of the worm on this shaft with the rack 116, the carriage may be moved laterally in the base 107 until a desired slide is in alignment 13

with the casting slot of the mold and the desired number on the rod 150 is visible through the opening in the shield 161, when the crank may be released and the spring 5 168 will force the rod 167 back into its seat in the column 152.

The block 168 at the rear of the base 107 is secured in the frame of the machine, and between it and the base is another block 169 10 which has an upper projection 170 adapted to limit the backward movement of the slides 122 and which is short enough to provide an opening 171 between the block 168 and the base 107 one or more springs 172 15 being suitably mounted beneath the block 169 for resiliently holding the block in position. The purpose of the springs 172 and the construction of the rear of the base, just described, is to facilitate the removal of 20 any one of the ejectors from their position in the slides 122 and to remove the slides from the carriage.

In the structure shown, the position of the ejector slides makes it necessary to provide 25 a new method of mounting the mold disk 106 and a re-arrangement of some of the parts of the machine in relation thereto. I provide an auxiliary frame 173 having a suitable base 174 adapted to be secured to 30 the main frame of the machine and in a central position with regard to the mold disk. Each end of the frame 173 has one of the centrally positioned bearings 175 and a pair of the bearings 176 arranged on opposite 35 sides of the center of the auxiliary frame. The rods 177 are slidably mounted in the bearings 176, extend outwardly from each end of the frame and have on their front end the mold disk support 178 which has its lower end 179 secured to the rods 177 and its upper bearing 180 adapted to serve as a 40 mounting for the mold disk.

The cross head 181 is secured to the rods 177 near the rear of the frame 173 and has 45 an upwardly extending yoke 182 adapted to engage the roller 183 on the mold cam lever 184 for advancing and retracting the mold disk in the usual manner. The mold turning pinion 2 is fixed to the shaft 4 which is 50 journaled in the central bearings 175 of the frame 173 and is composed of two parts independent of each other, as shown in Fig. 11, the forward portion 4 being slidable in the rear portion 185. Each of the portions 55 4 and 185 of this shaft is provided with a jaw clutch member 186 secured in position thereon by means of a set screw 187, or otherwise, the jaws of the two clutch members being adapted to intermittently engage 60 and disengage for revolving the mold disk 106 between the ejecting and casting operations, the action of the clutches being accomplished by means of a yoke 188 formed on and depending from the mold cam lever 65 184 and adapted to be held in engagement

with the clutch by means of a collar 189 secured to the pinion shaft 4 by means of a set screw 190.

The rear end of the shaft 185 is provided with a beveled intermittent gear 191 adapted to mesh with a similar but somewhat larger gear 192 on the main driving shaft 193 of the machine, and this end of the shaft 185 is suitably journaled in the bearing 194 on the main frame of the machine. The 70 75 number of teeth on each half of the gear 192 is sufficient to revolve the gear 191 one complete revolution; the number of teeth omitted between the above mentioned sets of teeth being sufficient to permit the engagement and disengagement of the clutch members 186, and the rotation of this gear being so timed with the mold cam that the clutch members may be engaged and disengaged as the mold disk 106 is advanced and 80 retracted. A sufficient number of teeth in the gear 192 may be omitted to provide a locking means while the clutch members are being engaged and disengaged.

The front end of the frame 173 is provided on the inside and in the center below the shaft 4 with a flat topped lug 196, which, when the clutch members 186 are about to disengage, is adapted to be engaged by the square block 197 secured to the pinion shaft 90 4, and while the clutch members are not in total engagement this block will remain seated on the flat top of the lug 196 and thus prevent the rotation of the pinion 2 and the mold disk 106 while the latter is on 95 100 the locking studs.

I do not conceive it to be necessary to limit the scope of my invention to the objects hereinbefore set forth nor to limit the invention to the exact structure shown, as it 105 may be necessary and expedient to somewhat alter the relative proportions and form of the structure of my mechanism in order that it may be adapted for use in connection with any type of line or slug casting machine, the 110 form of structure shown and the manner of adaptation of my mechanism to a machine being generally preferable for types of such machines now known and used.

Having thus described my invention, what 115 I claim as new and desire Letters Patent for, is:

1. A slug ejecting mechanism for linotype machines having a plurality of ejector blades arranged in sets about a common axis 120 and adapted to selectively coöperate with the mold disk.
2. A slug ejecting mechanism for linotype machines having a plurality of ejector blades arranged in sets about a common 125 axis, movable pivotally thereon and laterally with regard to the casting slot in the mold disk.
3. A slug ejecting mechanism for linotype machines having a plurality of sets of ejec- 130

10. A slug ejecting mechanism for linotype machines comprising a plurality of laterally adjustable ejector slides mounted on a common axis; a plurality of ejector blades pivotally adjustable on said slides, said blades being of different width and corresponding to standard slug lengths, and one of said blades being removable for adapting one of said slides to receive a blade of unusual width; and means for visibly indicating and selectively placing any one of the blades on any one of said slides in alignment and operative relation with the mold disk. 70
11. In a linotype machine, the combination of a mold disk; and an ejecting mechanism comprising a plurality of sets of laterally and pivotally adjustable ejector blades mounted on a common axis. 80
12. In a linotype machine, the combination of a mold disk; an ejecting mechanism comprising a plurality of sets of laterally and pivotally adjustable ejector blades mounted on a common axis; and means for selectively placing any one of said blades in operative relation to said mold disk. 85
13. In a linotype machine, the combination of a mold disk; an ejecting mechanism comprising a plurality of sets of laterally and pivotally adjustable ejector blades mounted on a common axis; means for selectively placing any one of said blades in operative relation to said mold disk; and means for visibly indicating the operative position of said blades. 90
14. In a linotype machine, the combination of a mold disk; and an ejecting mechanism comprising a plurality of ejector slides, each having a plurality of ejector blades of different width, said slides being laterally and said blades being pivotally adjustable in their relation to the mold disk. 100
15. In a linotype machine, the combination of a mold disk; an ejector mechanism comprising a plurality of laterally adjustable ejector slides; a plurality of pivotally adjustable ejector blades on each of said slides; and means for selectively placing any one of said slides in alignment with the casting slot of the mold disk. 110
16. In a linotype machine, the combination of a mold disk; an ejector mechanism comprising a plurality of laterally adjustable ejector slides; a plurality of pivotally adjustable ejector blades on each of said slides; means for selectively placing any one of said slides in alignment with the casting slot of said mold disk; and means for selectively placing any one of the blades on said slide in operative relation to said slot. 115
17. In a linotype machine, the combination of a mold disk; an ejector mechanism comprising a plurality of laterally adjustable ejector slides; a plurality of pivotally adjustable ejector blades on each of said slides; means for selectively placing any one of said slides in alignment with the casting slot of the mold disk; and means for visibly indicating the position of a blade when it is in such relation thereto. 120

one of said slides in alinement with the casting slot of said mold disk; means for selectively placing any one of the blades on said slide in operative relation to said slot; 5 and means for visibly indicating the operative position of said blades.

18. In a linotype machine, the combination of a mold disk; an ejector mechanism having a plurality of laterally movable ejector slides; a plurality of pivotally movable ejector blades on each of said slides; a removable blade on one of said slides; means for selectively placing a desired slide in alinement with the casting slot of said mold 10 disk; means for selectively placing a desired blade on one of said slides in operative relation to said slot; and means for visibly indicating the operative position of said blades.

19. In a linotype machine, the combination of a mold disk; an ejector mechanism having a plurality of laterally movable ejector slides; a plurality of pivotally movable ejector blades on each of said slides of different width; a removable blade on one of 25 said slides; means for securing a blade of irregular width on said slide in place of said removable blade; means for selectively placing a desired slide in alinement with the casting slot in said mold disk; means for 30 selectively placing a desired blade on one of said slides in operative relation to said slot; and means for visibly indicating the operative position of said blades.

20. In a linotype machine, the combination of a mold disk; an ejector mechanism having a plurality of laterally adjustable ejector slides; a plurality of pivotally mounted ejector blades of different width on each of said slides; means for removably 35 securing one of said blades to one of said slides for unusual widths of slugs; means for selectively placing one of said slides in alinement with the casting slot of said mold disk; means for selectively placing one of 40 the blades on one of said slides in operative position with regard to said slot; means for visibly indicating the operative position of said blades; and means for causing the engagement of said blades with said slot 45 for ejecting the slugs therefrom.

21. In a linotype machine, the combination of a mold disk; an ejector mechanism having a plurality of laterally adjustable ejector slides; a plurality of pivotally adjustable ejector blades on each of said slides, 50 all of said blades having a common axis and

being of different width; means for removably securing one of said blades to one of said slides; means for selectively placing said slides in alinement with the casting 60 slot of said mold disk; means for selectively placing said blades in operative relation to said slot; means for visibly indicating the operative position of said blades; means for causing the engagement of said 65 blades with said slot for ejecting the slugs therefrom; and resilient means on said slides for preventing a backward movement thereof during such engagement.

22. In a linotype machine, the combination of a mold disk; a base rigidly secured to the frame of the machine at the rear of said disk; a carriage laterally slidable in said base; and a plurality of sets of pivotally adjustable ejector blades having a common 70 axis and mounted on said carriage.

23. In a linotype machine, the combination of a mold disk; a base rigidly secured to the frame of the machine at the rear of said disk; a carriage laterally slidable in 80 said base; a plurality of ejector slides movable lengthwise of said base and mounted in said carriage; and a plurality of ejector blades of different widths and pivotally movable on said slides.

24. In a linotype machine, the combination of a mold disk; a base rigidly secured to the frame of the machine at the rear of said disk; a carriage laterally slidable in 90 said base; a plurality of ejector slides movable lengthwise of said base and mounted on said carriage; a plurality of ejector blades of different widths pivotally movable on said slides; and means for selectively placing said blades in operative relation to 95 said disk.

25. In a linotype machine, the combination of a mold disk; a base rigidly secured to the frame of the machine at the rear of said disk; a carriage slidable laterally in 100 said base; a plurality of ejector slides in normal alinement movable lengthwise of said base and mounted on said carriage; a plurality of ejector blades of different width movable pivotally on each of said slides; means for selectively placing said blades in 105 operative relation to said disk; and means for visibly indicating the operative position of said blades.

GEORGE E. MARLATT.

Witness:

ANNE HARTENSTEIN.
